UNITED STATES PATENT OFFICE.

LA VERNE W. NOYES, OF CHICAGO, ILLINOIS.

DESIGN FOR A STANDARD FOR DICTIONARY-HOLDERS.

SPECIFICATION forming part of Design No. 30,311, dated March 7, 1899.

Application filed August 22, 1898. Serial No. 689,367. Term of patent 14 years.

To all whom it may concern:

Be it known that I, LA VERNE W. NOYES, a citizen of the United States, residing at Chicago, in the county of Cook and State of Illinois, have invented and produced a new and original Design for a Standard for Dictionary-Holders, of which the following is a specification, reference being had to the accompanying drawings, forming part thereof.

10 The drawings illustrate a standard for a dictionary-holder embodying the design of my invention, Figure 1 being a perspective view of the standard, while Fig. 2 is a view in elevation, illustrating the form of the sections composing the standard; and Fig. 3 is a sectional view on line 3 3, Fig. 2.

15 As shown in the drawings, the leading and characteristic feature of my design consists in a standard formed of wire and arranged in a plurality of sections *a b c*, each section having a pair of strands *d d'*, which form the sides of a triangle, the apex of which consti-

tutes the foot of the section, while the base of the triangle, so to speak, is formed by the axial twisted portion *d*. Each section is provided with an intermediate twisted portion *e*, while above these portions another axial twisted portion *f* is provided.

20 While particularly adapted for the standard of a dictionary-holder, the design may be applied to other articles—as tables, chairs, and the like.

Having described my invention, what I claim as new, and desire to secure by Letters Patent, is—

25 The design for a standard for a dictionary-holder as herein shown and described.

In witness whereof I have hereunto subscribed my name in the presence of two witnesses.

LA VERNE W. NOYES.
